JOSEPH P. KEANE, OF WALLACE, IDAHO.

METHOD OF TUNNELING IN ROCK.

No. 877,779.

Specification of Letters Patent.

Patented Jan. 28, 1908.

Application filed April 29, 1907. Serial No. 370,885.

To all whom it may concern:

Be it known that I, JOSEPH P. KEANE, a citizen of the United States, residing at Wallace, in the county of Shoshone and State 5 of Idaho, have invented new and useful Improvements in Methods of Tunneling in Rock, of which the following is a specification.

My invention relates to the construction of tunnels and pertains especially to railroad 10 or other tunnels of large size through a rock formation. Its object is to provide for running large tunnels particularly through rock, in a more expeditious, economical and advantageous method than obtains in practice 15 at present.

The invention comprehends generally speaking the shooting of the cut in quick succession or substantially simultaneously partially with tape, and partially with electric fuse; thus avoiding the extra waiting for 20 the smoke to clear out from the face as is necessary when the center and sides are shot separately; the scraping up of the broken rock into the car and the method adopted for

25 the same; the shooting of the rock from the enlarged portion of the tunnel onto timbers from where it is dropped into cars, and the method employed to obtain this end, and the arrangement of the pockets for this purpose.

30 Having reference to the accompanying drawings—Figure 1 is a longitudinal section of a tunnel under construction. Fig. 2 is a section on line X—X of same.

The present invention is particularly designed 35 for tunneling through rock and where the tunnel is to be 16x22 feet or larger. It will be manifest however that the invention may be worked in smaller tunnels and in other formations.

40 In the practice of the invention an under-heading or passage-way A is run in on the bottom or track level *a* of the tunnel, in size from 9 to 10 feet in height and from 8 to 11 feet in width, having either the right or left

45 side of this heading correspond with what will be the permanent right or left side of the enlarged tunnel. This heading is excavated by putting in a V cut in the face, the holes converging from sides to center. The sides

50 are taken out by putting holes in parallel with the sides, or as nearly so as is practical. The holes are then loaded with powder, putting electric fuse in the V-cut holes, and tape

fuse in the side holes. The electric fuses are connected in series to battery wire which 55 goes back to the battery, located some 250 feet back from the face; with a weak cell battery, battery wires are tested to see if connections have been properly made; if the bell rings this shows the circuit is closed, or connections have been properly made. When 60 connections have been shown to be properly made, one man is allowed to remain at the battery and two men proceed to the face to "spit" the tape fuses; these men are to give 65 the battery man a signal with their lights just as they commence "spitting". When this signal is given the battery man, with watch in hand takes the time; after "spitting", the two men proceed to where the 70 battery man is located, behind proper protection, and after a sufficient length of time has elapsed to allow the fuses to burn below the collar of the holes the battery man connects up his wires and explodes the V-cut 75 holes, the side holes following in rapid succession.

If the rock is hard requiring a considerable amount of powder to break it, the broken rock will then be in suitable condition to load 80 into cars with a scraper. If the ground is so soft that it is not practical to use much powder with which to break it, and it breaks up into long irregular thin slabs it should be shoveled into the cars by hand, and before 85 shooting, $\frac{1}{2}$ inch sheet steel plates, not necessary to be shown, but about 3x4 feet in size, should be placed on the floor of the tunnel. The blast throws the rock down onto these 90 plates and the rock can easily be shoveled up. These plates are gradually worked up toward the face of the tunnel so that the loose rock may be picked down onto them and nearly all rock may be shoveled off from them: After the heading has advanced for a 95 distance of 200 to 250 feet the tunnel is enlarged as follows:

From 6 to 10 sets of timber as *b* are placed under the point where the enlargement is commenced, in such a manner that not less 100 than 3 sets are in advance at this point; the cap *c* of these sets being placed at a height of $5\frac{1}{4}$ feet more or less above the ties. These caps are covered with 3 inch plank or lagging *d* in which suitable chutes or openings *e* 105 are provided through which to remove the

broken rock. On top of this planking not less than one foot of loose broken rock as *f* is placed as a covering, to act as a protection and cushion against the rock cast down by the blasting. On top of this rock suitable blocking (not shown) may be placed on which to support the drilling machines and a round of holes is drilled as shown by #1 to #12 inclusive in Fig. 2. These holes may be all loaded with powder, and fired in rapid succession with tape fuse, or such numbers may be shot at a time as may be desired; but No. 1 hole must always be fired first, and loaded with only sufficient powder with which to break the ground on this hole. After this No. 1 hole is shot the planks will be covered with a sufficient quantity of material so it will be nearly impossible to break them. All the holes that it is possible to drill as such should be water holes, to be run just a little below the horizontal so they will carry water, or can be drilled with water. The side holes should be drilled as nearly parallel with the sides of the tunnel as is possible, and the top holes 7, 8, 9, 11, drilled as nearly parallel with the roof as possible; this is done in both cases to avoid as much as possible the breaking of an unnecessary amount of rock from the sides and roof of the tunnel. These holes will in each instance break approximately the section of ground as shown in cut, and should be fired in the order as shown in cut. After the holes as shown are shot the roof is then picked clean of all loose rock, and the broken rock is then drawn out into cars through the openings provided for this purpose; and after the rock is drawn sufficiently low the drilling machines are again set up on blocking on top of this remaining broken rock and another round of holes drilled as before.

All the broken rock is removed from the rear set of timbers, and these rear sets are placed in advance on which to shoot another round of holes. After these holes are fired all the face of the enlarged tunnel will be broken excepting that portion shown at the side as included in *a'*, *b'*, *c'*, *d'*, Fig. 2; to break out this portion of the ground a manchine is set on top of it, on either a bar, or tripod, and vertical holes 13 drilled in it close to the side of the tunnel down to the depth of the track. These are drilled so that there will be less ground to be broken toward the rear than toward the side, so that the broken ground will be thrown toward the rear falling on the sheet steel plates previously mentioned from which it is shoveled into cars; by having it fall to the rear it will not obstruct the main track.

If the heading is soft, the timbers on which the upper portion of the tunnel is later broken down, may be put in place in the head as it has been advanced, at a height of

about 5½ feet; this height being sufficient in 65 which to work an ordinary size mule.

It is preferable to bring air up to the enlarged face of the tunnel in pipes *h* placed over head, both compressed air and for ventilation. The air for the heading should be 70 conveyed along the permanent side of the heading; the compressed air pipe *i* on the floor of the tunnel outside the track, and the ventilation air pipe *h* at the angle of the side and roof. The ventilating pipe entering 75 the heading may be reduced to 12 inches in size and the rear length advanced; all the air may be forced to the heading in this reduced size of pipe or a portion only may be delivered at the heading face as it advanced. 80

Having thus described my invention, what I claim and desire to secure by Letters Patent, is—

1. The method of tunneling which comprehends the shooting of the cut substantially 85 simultaneously partially with tape and partially with electric fuse.

2. The method of tunneling which comprehends running a heading along the bottom or track level and along one permanent side 90 of the tunnel, building a staging with sufficient clearance underneath for the passage of the ore-cars, providing this staging with suitable openings over the line of travel of the ore-cars and then casting down the material on to the staging to the roof-line.

3. The method of tunneling which comprehends running a heading along the bottom of the track level and along one permanent side of the tunnel building a staging with sufficient clearance underneath for the passage of the ore-cars, providing this staging with suitable openings over the line of travel of the ore-cars and then casting down the material on to the staging to the roof-line and to 100 the width of the tunnel and subsequently blasting out the remaining rock at the side and bottom of the tunnel.

4. The method of tunneling which comprehends running a heading on the bottom of 110 the tunnel, erecting a staging in the heading and providing this staging with suitable hopper openings through which the material cast down from above may be fed into the ore-cars beneath, and which staging is arranged 115 to support the material cast down from above and then casting down the overhead material to the roof line upon said staging.

5. The method of tunneling which comprehends running a heading on the bottom of 120 the tunnel, erecting a staging in the heading and providing this staging with suitable hopper openings through which the material cast down from above may be fed into the ore-cars beneath, and which staging is arranged 125 to support the material cast down from above and then casting down the overhead rock to the roof line upon said staging, said over-

head material being blasted out by drilling holes into the face of the cut at suitable inclinations from the horizontal, filling the hole with a suitable blasting medium and then 5 discharging the blast in rapid succession beginning with the central hole, substantially as described.

In testimony whereof I have hereunto set my hand in presence of two subscribing witnesses.

JOSEPH P. KEANE.
